A. Blipham,
Attorney.

UNITED STATES PATENT OFFICE.

LEO SHLICK, OF BOSTON, MASSACHUSETTS.

BEATING ENGINE.

Application filed January 25, 1923, Serial No. 615,451. Renewed January 19, 1927.

This invention relates to machines commonly called beating engines, designed for the preparation of pulp in the manufacture of paper, and it has for its object the effecting of the improvements, in details of construction hereinafter set forth and illustrated in the accompanying drawings, in which Fig. 1 is a side elevation of a beating engine embodying my improvements, parts thereof being shown as broken away and in section. Fig. 2 is a plan view of the same, parts being broken away. Fig. 3 is a sectional view of a detail thereof. Fig. 4 shows a section of the beater roll. Fig. 5 is an end view of the deflector.

The beater roll 1 is supported within one end of the beater tub 2 by means of levers 3 pivoted at 4 to posts 5, and having its trunnions 6 rotatable in boxes 7 carried by the levers 3. As shown in Fig. 2, the tub 2 is approximately pear-shaped, the roll 1 occupying its narrower end 9, the enclosing top 10 rising considerably higher than the roll. Between this top 10 and a sloping floor 11 is an auxiliary floor 12 descending from a level above that of the topmost point of the roll down toward the larger end of the tub. A vertical wall 13 passes from a side of the tub to a hollow post 14 and forms, with the auxiliary floor 12 and the opposite wall of the tub, a channel for the passage of the stock from over the roll to the wider end of the tub. As the stock flows down this inclined channel, it sweeps about the hollow post 14 and thence down the inclined floor 11 to the beater roll 1 and the bedplate 15 coacting therewith. The better to deliver the stock to the roll, a wall 16 is formed between the floor 11 and the auxiliary floor 12, as shown in dotted lines in Fig. 2.

The top or hood 10 terminates near the post 14 at a level below that of the crest of the auxiliary floor or backfall 12, and to this termination is hinged a channel-contracting means or lip 17 which is curved both longitudinally and laterally, the longitudinal curvature being convex downward, and the lateral curvature being concave downward. The latter curvature is for the purpose of giving to the escaping stream of stock a more nearly circular cross section, and there-

by to diminish superficial friction thereto; while the longitudinal curvature is to reduce the resistance to the stream issuing from beneath it.

This lip or contractor 17 is hinged to the hood 10 at 19, and is adjustably held by a slotted ear 20 and a bolt 21; and its purpose is so to create a head between the level of the outer edge of the contractor and that of the crest of the backfall as to give a greatly increased speed of flow to the stock along the remainder of the channel to the roll and bed-plate.

To the crest of the backfall 12 is hinged a deflector 22 curved to present its concave surface toward the roll 1, and having its free end supported by pins 23 passing out through slots 24 in the tub-wall, and connected to the bearing boxes 7. A plate 25 penetrated by the pin 23 thereat and pressed tightly against the tub-wall by a helical spring 26,—as shown in Fig. 3,—serves to prevent the leakage of the stock through the slots 24.

At the free end of the front lever 3 is a supporting saddle 27 up against which is pressed a helical spring 29 which is in turn supported by a vertical screw rod 30, a nut 31 and a post 32. A hand wheel 33 operates a worm 34 engaging the cogged periphery of the nut 31 to enable the lever 3 to be raised and lowered as desired, the nearness of the beater roll to the bedplate being indicated by a pointer 35 carried by the rod 30 in the field of an index 36.

The adjustment of the front lever 3 is transmitted to the rear lever 3 by means of a cross shaft 37, crank arms 39 rigid therewith, and connections between these crank arms and the levers. One or both of these connections may be provided with a turn-buckle 40 for their accurate adjustment.

I prefer to form the beater tub channel ovate in cross section, as shown in Fig. 1, in order to reduce surface friction and thereby to increase the speed of flow.

A discharge pipe 41 provided with a dumping valve 42 is located through the floor 11 close to the bedplate 15, as illustrated in Fig. 1, for the withdrawal of the fully treated pulp.

It is preferable to have the fly-bars 43 rearwardly inclined from the points where they emerge from the roll 1 in order to more efficiently affect the stock 5 and to throw it up over the deflector 22. Each fly bar rests at its inner edge upon a shelf 44, and is retained in place by a wooden wedge 45 driven in between two of them.

10. In addition to having the fly-bars rearwardly inclined with respect to the radii of the beater roll, I have the surface of each on its side of advance, made convex, for further improving their action on the stock.
15. Hinged or otherwise secured beneath the backfall adjacent the breast of the beater roll 1 is an apron 46 whose inner surface is eccentric to the beater roll, and whose lower edge or lip is close to the roll and spaced 20 below the level of the axis of the beater roll.

The purpose of the adjustable connection between the deflector 22 and the bearing box 7 is to throw the free edge of the deflector up out of the way of the flybars whenever 25 the beater roll happens to jump because of some especially large lumps of stock. This connection consists of oppositely threaded rods and a turn buckle of well known form.

I prefer to bolt the posts 5 and 32 to the 30 sides of the tub foundation 50, so that the entire machine composes an inflexible whole, and does not have to depend upon the supporting floor for its rigidity.

The operation of the machine is as follows: As the stock flows down the inclined floor 11 it is received between the beater roll 1 and the bedplate 15 and given a more or less complete maceration. It is thence carried up and over the roll and the deflector 22, and down the backfall 12. The retarding gate 17 being suitably adjusted and the beater roll sufficiently rapid, the stock accumulates between the backfall and the gate until it remains on the level with the crest 45 of the backfall,—which is the topmost point of the deflector. The head thus gained causes the stock to issue from beneath the gate with a high velocity and thereby traverse the remainder of the channel to the beater roll with such a speed as to ensure 50 against deposits of the pulp, and to permit of a considerably greater pulp-production per unit of time.

What I claim is:

55. 1. A beating engine comprising a tub, a beater roll, a back fall higher than the topmost point of the beater roll, an upwardly curved deflector pivoted at one end to the back-fall and presenting its free edge close 60 to and above the beater roll and on a line beyond said topmost point.

2. A beating engine comprising a tub, a beater roll, a back-fall having an elevated crest, a beater roll hood spaced above said 65 members and having its delivery end below

the level of said crest, and a lip pivoted to the extremity of said end and provided with means for its angular adjustment and for rigidly retaining it at any desired point of adjustment.

3. A beating engine comprising a tub, a beater roll, a back-fall and a concavo-convex apron hinged at its upper edge to said back-fall and presenting its concave face toward said roll and its lower edge closer thereto than its surface away therefrom.

4. A beating engine comprising a beater tub, a beater roll having trunnions, pivotally supported arms sustaining said trunnions, means for causing said arms to move equally, a vertically adjustable rod, a spring carried by said rod and supporting one of said arms, a bed-plate and an index and an indicator carried by said rod and arm respectively to show the degree of pressure upon the stock 85 between the roll and bedplate.

5. A beating engine comprising a tub having elevated sides and an elevated back-fall, a beater roll, vertically movable means rotatably supporting said roll, a deflector pivoted to said back-fall, a rod passing outwardly through the wall or side of said tub, the latter being vertically slotted therefor, said rod supporting the free end of said deflector, connection between the outer end of said rod and said roll-supporting means, a plate penetrated by said rod, and a spring adapted for pressing said plate against the surface of said wall or side and thereby to prevent the escape of liquid matter through said slot.

6. A beating engine comprising a tub, a beater roll, a back-plate, yieldingly supported means for the beater roll, a spring holding said means, and an index connected with said means for showing the degree of pressure upon the stock between the roll and bed-plate.

7. In a beating engine, a beater roll having fly-bars at an acute angle with the radii thereof in a direction opposite the rolls peripheral travel, the surface of each fly-bar on its side of advance being convex and the fly-bars being of substantially uniform thickness throughout.

8. In a beating engine, a tub having its channel elliptical in cross section, the outer surface thereof being more flatly curved than its inner surface.

9. A beating engine comprising a beater tube, a beater roll having peripheral slots, and flybars having their bases set into said slots, and their blades at an angle with respect to their bases, the faces of the blades which engage the stock being gradually curved away from their points of juncture with their bases.

10. A beating engine as set forth in claim 9 having the blades and bases of the fly-bars meeting at their junctures in a substantially 120

segmental manner in order to gradually and more efficiently accelerate the stock with a lower power consumption.

11. A beating engine as set forth in claim 5 having the junction each blade with its base at the circumference of the roll, and the gradual curvature of the blades beginning at the said juncture and continuing to the cutting edges thereof.
- 10 12. A beating engine as set forth in claim 9 having the curvature of the blades more pronounced adjacent the roll and becoming less curved as each approaches its cutting edge.
- 15 13. A beating engine comprising a beater tub, a vertically movable beater roll therein, and a hinged deflector presenting its free edge close to and above said roll, and connection between said free edge and the supports of said roll, whereby the upward movements of the latter are transmitted to the deflector.
- 20 14. A beating engine as set forth in claim 13 having adjustable connection between the

deflector and trunnions whereby the vertical 25 movements of the roll are communicated to the deflector.

15. A beating engine comprising a beater tub, a beater roll having trunnions, vertically movable supports for said trunnions, 30 a deflector hinged above said roll and presenting its free edge close to said roll, said tub having a slot in a side wall adjacent said deflector, a rod rigidly projecting through said slot from said deflector, connection between the outer end of said rod and the trunnion-support below, and means for preventing leakage of the stock through said slot.

16. A beating engine comprising a tub, a beater roll, and bed-plate, the floor of the tub-channel sloping downward toward the bed-plate, the pitch of the incline gradually steepening as the bed-plate is approached.

In testimony that I claim the foregoing 45 invention, I have hereunto set my hand this 22nd day of January, 1923.

LEO SHLICK.
